UNITED STATES PATENT OFFICE.

HARLON F. ONG, OF PORTLAND, OREGON.

FOUNTAIN-SYRINGE ATTACHMENT.

1,099,760.

Specification of Letters Patent.

Patented June 9, 1914.

Application filed December 31, 1913. Serial No. 809,682.

To all whom it may concern:

Be it known that I, HARLON F. ONG, a citizen of the United States, and a resident of Portland, in the county of Multnomah 5 and State of Oregon, have invented a new and Improved Fountain-Syringe Attachment, of which the following is a full, clear, and exact description.

This invention relates to surgery, and 10 has particular reference to fountain syringe devices or attachments for douching, medicating, and cleansing the vaginas of women.

Among the special objects of the invention is to provide an oval or oblong type 15 of nozzle attachment having one end adapted to enter and substantially close or obstruct the vulva, whereby the medicated and cleansing fluids may be injected as desired but will be prevented from being discharged 20 except in the manner provided for.

Another object of the invention is to utilize the special form of nozzle for the purposes, first, of supplying in it a medicament in tablet or dry form which may pass into 25 solution with the fluid delivered thereto from a syringe fountain, or the like, and secondly, to make use of the large body of air contained in the nozzle at the beginning of the operation, such air serving to cause 30 swirling and bubbling, and being forced inwardly therefrom serves to balloon or distend the tissues and thereby markedly increase the distribution and cleansing and healing properties of the fluid medicament.

35 A still further object is to facilitate the control of admission of fluid to and delivered from the affected parts according to the patient's sense of pressure resulting from the ballooning action above referred to, special 40 valve means being resorted to, under certain conditions, to control the fluid circulation or discharge.

The foregoing and other objects of the invention will hereinafter be more fully described and claimed and illustrated in the 45 drawings forming a part of this specification in which like characters of reference indicate corresponding parts in all the views, and in which—

50 Figure 1 is a perspective view of a preferred form of the invention; Fig. 2 is a longitudinal section of the attachment; and Fig. 3 is a detail view of one form of valve mechanism which may be employed in connection with the nozzle attachment.

The several parts of the device may be made of any suitable materials, and the relative sizes and proportions, as well as the general design of the mechanism, may be varied to a considerable extent without departing from the spirit of the invention hereinafter more fully set forth and specifically claimed.

Referring more particularly to the drawings for a description of the mechanism, I 65 show at 10 an oval or globular nozzle attachment of considerable capacity and having an open inner end 11 and a similar outer end 12 preferably in alinement with each other and having on one side, preferably at a point not far remote from the outer end, an inlet neck 13 for attachment of a fountain hose 14 or other means for conveying fluid into and through the nozzle. The form and size of the nozzle makes it possible to introduce a 70 medicament in the tablet or dry form, as suggested at 15, which will be in position to be acted upon and readily dissolved by the water introduced through the tube 14 and by it conveyed to the affected parts. 75 The outer end 12 is adapted to be kept closed during the first part of the operation, either by the patient's finger alone or in connection with any suitable auxiliary device such as a soft rubber cap 16 coöperating 80 with an annular concave valve seat 17 surrounding the outlet. After the treatment has progressed as above described, the 85 cleansing fluids may be discharged through the nozzle and from the outer end or outlet 90 12.

Having thus described my invention, I claim as new and desire to secure by Letters Patent:—

The herein described nozzle for the purposes set forth, the same comprising a hollow, oval, globular member having a smooth inner end and an outer end comprising a valve seat, said ends having openings in alinement with each other, said device also 95 being provided with an inlet neck on one side not far remote from the outlet opening.

In testimony whereof I have signed my name to this specification in the presence of two subscribing witnesses.

HARLON F. ONG.
